UNITED STATES PATENT OFFICE.

ARTHUR B. HAUGEN, OF CALVIN, NORTH DAKOTA.

MOUSE-TRAP.

1,053,597.

Specification of Letters Patent. Patented Feb. 18, 1913.

Application filed April 15, 1912. Serial No. 690,757.

To all whom it may concern:

Be it known that I, ARTHUR B. HAUGEN, a citizen of the United States, residing at Calvin, in the county of Cavalier, State of North Dakota, have invented certain new and useful Improvements in a Mouse-Trap; and I do hereby declare the following to be a full, clear, and exact description of the invention, such as will enable others skilled in the art to which it appertains to make and use the same.

This invention relates to new and useful improvements in mouse traps.

An object of this invention is the provision of a mouse trap which can be constructed from strands of non-ductile wire thus rendering the same comparatively simple and inexpensive to manufacture, reliable and efficient in use and readily operated.

With the above and other objects in view, this invention resides in the novel features of construction, formations, combinations and arrangements of parts to be hereinafter more fully described, claimed and illustrated in the accompanying drawings, in which:—

Figure 1 is a perspective view illustrating my improved trap sprung, and Fig. 2 is a similar view showing the same set.

Referring to the accompanying drawing by similar characters of reference, the numeral 5 designates generally my improved trap which consists of a main body or frame 6 constructed preferably from a continuous strand of non-ductile wire bent to produce equal length opposite side members 7 and 8 connected at one end of the frame by an integral end member 9, and at the opposite end of the said frame by an opposite end member 10 which is formed integral with the side member 7 and bent at its terminal and intermediate its ends to produce eyes 11 and 12 through the latter of which is extended the adjacent end of the side member 8 which is then bent back upon itself as at 13 a suitable distance at which point it is offset to produce an inwardly extending finger 14.

The side members 7 and 8 are formed with registering eyes 15 which support a movable jaw 16 arranged to coöperate with the stationary jaw 17 formed at one end of the frame 6. The jaw 16 is formed, like the frame 6, from a single strand of non-ductile wire, bent to produce opposite side members 18 and 19 connected at the free ends of the

jaw by an integral end member 19'. The side member 18 of the jaw 16 has formed thereon an inwardly extending end member which will be hereinafter termed as a shaft 20, the said shaft running parallel to the end member 19' and being extended through the eye 21 formed upon the inner end of the side member 19. It will be thus seen that the jaw 16 is hingedly secured to the intermediate portions of the frame 6 in such manner that the end member 19', when the trap is sprung will coöperate with the end member 9 of the frame, and that the side members 18 and 19 will coöperate with the side members 7 and 8, in which position the jaw 16 is yieldingly forced by the spring 22 which surrounds the shaft 20 between the eyes 15 and has one end bent to engage the finger 14, and its opposite end bent to engage the side member 18.

A connecting bar 23 is attached at its terminals to the side members 7 and 8 and is bent intermediate its ends to produce an eye 24 which is connected to an eye 25 formed intermediate the ends of the bell crank lever 26 which has the terminals of its arm bent to produce loops or eyes 27 and 28 the former of which receives a locking rod 29 which is pivoted at its opposite end 85 to the eye 11 as shown at 30. It will thus be seen that the bell crank lever 26 acts as a treadle or trip member.

In setting the trap the jaw 16 is forced backwardly against the tension of the spring 22 until the end 19' thereof engages the side members 7 and 8 adjacent the end member 10. The locking lever is then placed over the end member 19' and the free end thereof is inserted through the loop 96 or eye 27.

Bait is applied to the loop or eye 28 and obviously when an animal endeavors to reach the same, the lower arm of the bell crank lever 26 will be swung downwardly forcing the upper arm thereof outwardly causing the loop 27 to be disengaged from the adjacent end of the locking lever 29 thus causing the movable jaw 16 to be swung by the tension of the spring 22 to engage the stationary jaw 17 thus holding any portion of the animal which is disposed between these said jaws against removal.

The trap herein described is especially adapted for catching small animals such as mice, rats, or the like, but it is to be understood that the same can be made on a larger

scale or in any size which will adapt the trap for larger animals, and it should also be mentioned that various minor changes in the details of construction can be resorted to within the scope of the appended claims without departing from or sacrificing any of the advantages of the invention.

From the foregoing disclosures taken in connection with the accompanying drawing it will be manifest that a trap of the nature described is provided which will fulfil all of the necessary requirements of such a device.

Having thus fully described this invention what I claim as new and desire to protect by Letters Patent, is:—

1. A trap consisting of a frame comprising opposite side and end members, one of said side members being bent to produce a finger, a bar connecting the side members of the frame, a treadle pivoted to said bar, a shaft rotatable within said frame, a jaw carried by said shaft for coöperation with one end of the frame, a locking lever pivoted to one end of the frame for engagement with the jaw and treadle, and a spring surrounding the shaft and engaging one side of the jaw and the finger.

2. A trap such as described, comprising a frame formed from a strand of wire bent

to produce opposite side and end members, said side members being formed with registering eyes, one of said end members being bent to produce an intermediate and a terminal eye, one of the side members being extended through the terminal eye and being bent backwardly upon itself and offset to produce an inwardly extending finger, the opposite end member and adjacent portions of the side members constituting a stationary jaw, a bar connecting the opposite sides of the stationary jaw, a bell crank lever pivoted to the bar and formed with terminal loops, said bell crank lever producing a treadle, a locking lever secured to the intermediate eye of the end member for engagement with the loop at one end of the treadle, a shaft journaled in the eyes of the side members, a movable jaw carried by the shaft for coöperation with the stationary jaw, and a spring surrounding the shaft and engaging one side of the movable jaw and the finger.

In testimony whereof, I affix my signature, in presence of two witnesses.

ARTHUR B. HAUGEN.
